UNITED STATES PATENT OFFICE.

CHARLES JOSEPH MOLTZ, OF RICHMOND, VIRGINIA.

SCREW JACK.

Application filed October 5, 1921. Serial No. 505,546.

To all whom it may concern:

Be it known that I, CHARLES J. MOLTZ, a citizen of the United States, residing at Richmond, in the county of Henrico and State of Virginia, have invented certain new and useful Improvements in Screw Jacks, of which the following is a specification.

This invention relates to screw jacks of the portable type, and has for its object to provide a jack with improved means for raising and lowering the screw, the action being produced by a ratchet nut operated by a lever and a double-acting pawl which can be shifted to engage either way and thereby either raise or lower the screw. A further feature of the invention is a spring to hold the head against the object being lifted while the pawl is in neutral position.

The invention is illustrated in the accompanying drawing in which Fig. 1 is a vertical section of the jack. Fig. 2 is a top plan view with a cover plate removed to show the pawl.

The standard of the jack is indicated at 6, resting on a base 7. The standard is hollow, and rectangular in section and receives the squared head 8 at the lower end of a screw 9, the upper end of which has a rocking head 10 connected to the screw by a pivot pin 11 which will adjust itself to various angles. A nut 12 fits on the screw and rests at 13 on the top of the standard, and this nut can be turned to raise or lower the screw. The nut comprises a barrel or tubular body, and a flange provided with notches 14, said flange being confined between upper and lower plates 15 and 16 which will form a casing between which is enclosed a double-acting V-shaped pawl 17 having at each end a bevelled inturned tooth 18 either of which may be engaged with the notches 14, the pawl being pivoted between the plates by a pivot pin 19. The position of the pawl is controlled by a pin 20 pressed by a spring 21 which has a bevelled end to engage against either side of the point 22 at the apex of the pawl. The casing plates 15 and 16 are bolted together as indicated at 23, and the lower plate has integral therewith a lug 24 which fits in one end of a socket piece 25, to which it is bolted, the other end of the socket being

adapted to receive a lever handle 26 which may be removed when not in use. A spring 27 is coiled around the screw below the nut 12, being confined between said nut and shoulder 30 on the inside of the standard 6. The nut 12 and the handle parts mounted thereon are retained in position with respect to the standard 6 by means of a brace 32 the lower end of which is attached to the standard 6 by screws 33, and the upper end of which is bent inwardly as indicated at 34 to project over the nut 12, the projecting part having an opening through which the upper end of the nut 12 extends, and the brace is held in position by a small nut 31 screwed on the threaded upper end of the nut 12. The brace also carries a curved plate 35 which is pressed against the outer edge of the nut 12 by a coiled spring 36 between said curved plate 35 and the brace 32, and said plate binds against the nut with sufficient pressure to prevent the same slipping except when turned by the handle 26. The standard may also be provided with a pin 28 extending upwardly and serving as a handle to hold the jack steady or to set the same in place.

In operation, the jack is set under the object to be lifted, and the pawl 17 is swung to engage the point 18 thereof, the pin 20 then serving to hold the pawl as set. Then by swinging the handle back and forth the pawl slips on the back stroke and engages in the forward stroke, the pin 20 yielding to permit the movement and the nut 12 is thereby turned and traveling down on the screw when the latter is lifted to raise the weight. To lower the weight the pawl is shifted to the opposite position and operated in a similar manner. Rotation of the screw is prevented by the squared head 8 in the hollow of the standard. In Fig. 2 the pulley is shown in neutral position, but the active positions are obvious.

I claim:

1. A jack comprising a standard, a screw mounted thereon, means to raise or lower the screw, including a nut resting on the standard and fitting on the screw, and a spring coiled around the screw between the nut and the standard.
2. A jack comprising a standard, a screw

mounted thereon, means to raise or lower the screw including a nut resting on the standard and fitting on the screw, and a brace attached to the standard and extending around 5 above the nut to hold the same on the standard, said brace being provided with a spring friction plate bearing against the nut.

In testimony whereof I affix my signature, in presence of two witnesses.

CHAS. JOSEPH MOLTZ.
